RADIO TUNER

Peter C. Jones, Dayton, Ohio

Application October 1, 1945, Serial No. 619,731

6 Claims. (Cl. 171—119)

(Granted under the act of March 3, 1883, as amended April 30, 1928; 370 O. G. 757)

1

The invention described herein may be manufactured and used by or for the Government for governmental purposes without payment to me of any royalty thereon.

This invention relates to radio tuning and has particular reference to a tuning device for all wave radios.

An object of the invention is to provide a tuning device which combines the functions of a coil and a variable condenser, to the end that both space and material will be conserved.

Another object is to provide a tuning device which is adaptable to a linear tuning dial without strings and pulleys for operating the frequency indicating pointer.

Another object is to provide a tuning device in which a greater range of frequencies is had than with those of conventional design.

Further objects and advantages will be evident from a consideration of the following description, taken in conjunction with the drawings, wherein:

Fig. 1 is a perspective view of the tuner.

Fig. 2 is a longitudinal section through the guide rods and coils.

Like reference characters refer to like parts throughout the several views.

Referring now to the drawings, two tubular guide rods 10 are press-fitted at the ends into end heads 12 which constitutes a framework for the device. Pins 14 may be used to further secure the guide rods in the heads.

A carriage 16 is slidable longitudinally on the guide rods and is propelled therealong by a rack and pinion movement, the rack 18 of which may preferably be set in notches in the heads 12 and fastened by screws 20, and the pinion 22 of which may have its rotative bearing on a shaft 24 (see Fig. 2) which extends transversely through the carriage 16. A knurled thumb and finger knob 26 is provided for rotating the pinion, which may preferably be provided with some form of anti-backlash means, the means shown being well known in the art and consisting of making the gear in two layers, each layer with an arcuate slot 27, and placing a small coil spring 29 in the slots with one end of the spring reacting against the end of the slot of one layer and the other end of the spring reacting against the opposite end of the slot of the other layer.

Tapped mounting holes 28 are provided in the heads 12 for securing the device in a radio cabinet, slots in the face of the cabinet (not shown) being provided for the knob 26 and for a pointer 30 which is fast on the carriage 16 and may

2

reach through the slot provided for it and cooperate with a linear dial on the face of the cabinet to indicate the frequency setting. Inductance can be plotted in terms of physical movement of the pointer 30 by the carriage 16.

The arrangement shown may preferably be used for the reason that it provides a maximum of linear adjustment in minimum space. The alternative, however, of securing the rack 18 to the carriage 16, and providing rotative bearing for the shaft 24 in one of the heads 12, is considered to be within the scope of the invention. So also, a roller may be placed on the carriage 16 under the lower edge of the rack 18 whereupon the rack need not be supported on the right-hand end head and this head may be eliminated if desired.

A single-layer primary coil 32, Fig. 2, is shown as being wound directly on the guide rod 10, the coil beginning at the binding screw 34, and extending through a longitudinal groove in the rod 10 to the opposite end, then being wound on the outside of the tube and ending at the terminal screw 36. A thin nonconductive cover 38 is shown as surrounding the primary coil 32.

Although shown in a fixed position, the primary coil may be made movable in increments controlled by the carriage 16. This method will control the coefficient of coupling between the primary and secondary and conceivably the coefficient of coupling may be kept constant over the entire frequency range of the device. Moreover, it is to be understood that in this device the change of frequency may be made a linear function.

A single-layer secondary coil 40 is formed from a length of strip stock about .011" thick and approximately .125" wide wound edgewise into the form of a closed-coil spring, the first and last turns being connected to the binding screws 42 and 44 respectively. Parts 32 through 44 when assembled may be broadly designated by the numeral 46.

The oscillator coil 48 is in every respect like the coil 46 except that it is shorter, a hub 50 being provided on the carriage 16 to take up the difference in length. Slugs 52 and 54 of compressed powdered iron are fixed in the ends of the guide rods 10 within the coils 46 and 48 respectively.

The operation of the device is substantially as follows:

When the tuning knob 26 is turned clockwise, the carriage 16 moves from the extreme left position shown to the right, and stretches out the

secondary coils 40 and 40a thereby lengthening the flux path and coincidentally increasing the space between the flat sides of the coils, whereby the normal inductive and capacitative reactance are decreased simultaneously thereby increasing the frequency. Because of the slugs 52 and 54, the ratio of lowest to highest frequency is increased. Moreover, since the capacitance is increased or decreased in the coil itself, no other variable condenser is required.

While I have shown and described a tuning device having an oscillator coil in the set it will of course be understood that in situations where this coil is not needed it may be omitted.

Having described an embodiment of my invention, I claim:

1. A radio tuning device which comprises, in combination, a hollow guide rod, an end head at each end of said hollow guide rod, a rack supported at its ends on said end heads, a carriage 20 slidable on said hollow guide rod intermediate said end heads, an anti-backlash pinion in mesh with said rack, a shaft for said pinion having rotative bearing in said carriage, a thumb and finger knob associated with said shaft and pinion for rotating said pinion, a primary coil wound on a part of said rod adjacent one end head and fixed against endwise movement on said hollow guide rod, the beginning and end of said primary coil being attached to said one end head, a secondary coil freely surrounding said primary coil and having one end attached to said one end head and the other end secured to said carriage, said secondary coil being composed of relatively thin but wide strip of conductive material wound edgewise, whereby movement of said carriage away from the end of said primary coil lengthens said secondary coil, thereby increasing the distance between the turns of said secondary coil, and a slug of compressed powdered magnetic material positioned within the hollow of said guide rod within the length of said primary coil.

2. A radio tuning device which comprises, in combination, a guide rod, an end head fast on the end of said guide rod, a rack supported at its end on said end head, a carriage slidable on said guide rod, a pinion in mesh with said rack, a shaft for said pinion having rotative bearing in said carriage, a knob associated with said shaft and pinion for rotating said pinion, a primary coil wound on a part of said rod adjacent the end head and fixed against endwise movement on said rod, the beginning and end of said primary coil being attached to said end head, a secondary coil freely surrounding said primary coil and having one end attached to said end head and the other end secured to said carriage, said secondary coil being composed of relatively thin but wide strip of conductive material wound edgewise, whereby movement of said carriage away from the end of said primary coil lengthens said secondary coil, thereby increasing the distance between the turns of said secondary coil, and a magnetizable core positioned in said guide within the length of said primary coil.

3. A radio tuning device which comprises, in

combination, a guide, a head at the end of said guide, a rack supported at its end on said head, a carriage slidable on said guide, a pinion in mesh with said rack, means for providing rotative bearing for said pinion in said carriage, a knob associated with said pinion for rotating said pinion, a primary coil wound at one end of said guide adjacent the end head and fixed against endwise movement with respect to said guide, the beginning and end of said primary coil being attached to said head, and a secondary coil freely surrounding said primary coil and having one end attached to said head and the other end secured to said carriage, said secondary coil being composed of relatively thin but wide strip of conductive material wound edgewise whereby movement of said carriage away from the end of said primary coil lengthens said secondary coil thereby increasing the distance between the turns of said secondary coil.

4. A radio tuning device which comprises, in combination, a guide, a carriage slidable on said guide, means to slide said carriage along said guide, a primary coil wound on said guide adjacent one end and fixed against endwise movement thereon, and a secondary coil freely surrounding said primary coil and having one end fixed with respect to said guide and the other end secured to said carriage, said secondary coil being composed of relatively thin but wide strip of conductive material wound edgewise, whereby movement of said carriage away from the end of said primary coil lengthens said secondary coil thereby increasing the distance between the turns of said secondary coil.

5. A radio tuning device which comprises a primary coil of fixed length, a secondary coil having one end fixed with respect to the primary coil and the other end movable axially, said secondary coil being composed of close-up turns of a relatively wide but thin strip of electrically conductive material wound edgewise, and means to stretch the turns of the secondary coil apart whereby the inductance and capacitance is simultaneously decreased.

6. A radio tuning device which comprises a primary and a secondary coil, said secondary coil being composed of turns of a relatively wide but thin strip of electrically conductive material coiled edgewise, and means to progressively change the relation between the axial length of the secondary and the axial length of the primary, whereby the inductance and capacitance is simultaneously altered.
